TOBACCO PRODUCT AND METHOD OF
OBTAINING THE SAME

Mayne R. Coe, Washington, D. C.

Application November 18, 1936, Serial No. 111,441

9 Claims. (Cl. 131—6)

(Granted under the act of March 3, 1883, as
amended April 30, 1928; 370 O. G. 757)

This application is in part a continuation of my application Serial No. 701,733, filed December 9, 1933.

This application is made under the act of March 5 3, 1883, as amended by the act of April 30, 1928, and the invention herein described, if patented, may be manufactured and used by or for the Government for governmental purposes without the payment to me of any royalty thereon.

10 This invention relates to tobacco products and the method of treating the tobacco for obtaining the same.

One of the objects of the invention is the provision of a new and improved method and means 15 of treating tobacco so that the products may possess a superior flavor, aroma and smoking quality and further that this product may retain such flavor, aroma and smoking quality until used.

Another object of the invention is the provision 20 of a new and improved method of treating tobacco whereby the long period of preparing the tobacco for consumption may be materially shortened without injuriously affecting the flavor, aroma and smoking quality of the same.

25 A still further object of the invention is the provision of a new and improved method of enhancing the flavor, aroma and smoking quality of packaged tobacco and for preserving the same over long periods of time and to assist in the aging 30 thereof.

Another object of the invention is the provision of a new and improved tobacco product having an improved flavor, aroma and smoking quality.

35 A further object of the invention is the provision of a new and improved tobacco product in which the volatile nicotine content is materially reduced for the purpose of reducing irritating qualities in tobacco smoke.

40 As at present practiced, the process of treating harvested tobacco to convert it into the finished or packaged product of commerce ready for consumption by the ultimate consumer is a long and complicated one. It involves at least the step known as "curing" and with most processes, the 45 step known as "sweating" or "fermentation". A third step is often included, known as "aging".

It is common practice in the curing of tobacco to sever the stalks adjacent to the ground when the leaves reach a certain stage in the ripening 50 process, and the stalks hung in the barn for drying. In other methods, the leaves are stripped from the growing stalks and hung up in barns for drying. This is called "curing" the tobacco and usually requires from one to several months.

55 Other methods of curing, such as exposure to the

direct sun's rays, called "sun curing"; subjecting the cut tobacco plants after acquiring a rich yellow color, to the effect of slow fires lighted on the barn floors, called "fire curing"; and curing the plant by "flue-heat"; are also practiced. 5

Great skill and care is required during the so-called "curing" period. If the weather is too dry, moisture in the form of steam is added, and if there is too much moisture in the air, fires are employed to remedy this defect. During this 10 period, numerous deteriorating agents may develop, such as white mold, yellow and blue mold, stem rot, and many others, some of which may destroy an entire crop within as short a time as 15 two days.

During the curing period, many chemical changes take place within the curing leaves, some of which are known and some of which are not. For instance, the starch and sugar content undergoes changes during the early stages of the curing 20 period, and in the later stage, enzymes appear to be active. Changes also occur in the color and flavor of the tobacco.

After the curing period, the leaves are stripped from the stalk and are made into bunches or 25 "hands" of six to twenty leaves or more by twisting another leaf around the lower or stem end of the "hand".

The tobacco is then ready for the "sweating" or 30 "fermentation" period, as it is called. This step develops in the leaves, the characteristic qualities of the commercial article. It is during this period that much of the desirable aroma, flavor and smoking quality are developed.

This step is usually accomplished by stacking the "hands" in heaps when the tobacco is "in case", that is, when it is more or less moist so that it is not friable. The mass is kept in a moderately warm place and soon begins to "heat". Extreme care must be taken to prevent the rise of the temperature above 120° F. or at most, 130° F. It is then restacked from time to time to prevent it from becoming too warm. The mass may be restacked as much as five or six times during the 40 fermentation period which may last from one to 45 two months or longer.

During this period, numerous chemical changes occur, some of which affect the nicotine, ammonia content and other nitrogenous constituents, some 50 the color, flavor and aroma, and many others that are not understood. Even the causes for certain of the changes are in dispute.

After the fermentation, the tobacco may be subjected to what is known as the "aging" step 55 which comprises packing the tobacco tightly into

bales or hogsheads or other containers and storing the same in warehouses or the like under moderate and fairly uniform temperature for a number of years. Further changes take place during this period that develop mellowness and the desirable flavor and aroma characteristic of the better class of tobacco.

The present invention seeks to improve the commercial product by treating tobacco at any period in its processing stage, or after it is packaged for consumption, by a new and improved method whereby a product is developed having a milder and more desirable flavor, aroma and greater freedom from irritating qualities than would otherwise be produced.

It has been found by experiment, for instance, that if the tobacco be enclosed in a wrapper which admits only those light rays above 4900 Angstrom units of the spectrum during the "curing" operation, that a product is obtained having a superior smoking quality, flavor and aroma due to certain photo-chemical changes caused by such rays when the tobacco is subjected to them alone during the curing operation.

It has also been found that tobacco products while being cured and prepared for use by the usual processes, suffer a rapid loss of flavor and aroma from exposure to ordinary light or sunlight. This is particularly noticeable after it has been prepared for market in the form of smoking and chewing tobacco or as cigarettes and cigars.

It has been found, however, that not all light rays are harmful to this air cured plant product, and that the harmful wave lengths of light are below 490 Angstrom units of the spectrum. Specifically, it has been found that exposure of this plant product to ultra-violet, violet and blue wave lengths of light results in a loss by the product of mildness, flavor and aroma. Tobacco in its various forms exposed to ordinary light, which includes ultra-violet, violet and blue light rays acquires a rank smoking quality and suffers a loss of that pleasing aroma and mildness so prized by the users of tobacco.

While it is found that the light rays specified above lying below 4900 Angstrom units of the spectrum are definitely harmful to the cured tobacco products, wave lengths of light above 4900 Angstrom units of the spectrum, when admitted to the products, have a decidedly beneficial effect in that the desirable flavor and aroma and smoking quality are enhanced.

It is further found, however, that the wave lengths of light above 4900 Angstrom units of the spectrum vary in respect to their preservative and enhancing quality in the particular above disclosed. It is found, for example, that chlorophyll green rays of light may be admitted to the product after it has been prepared for consumption with extremely beneficial results. Smoking tobacco, cigarettes and cigars protected for a period of fifteen days by a transparent or translucent chlorophyll green screen or wrapper were mild in smoking quality, that is, they were less irritating to the throat, possessed a fragrant tobacco aroma and were very pleasing to the smoker, while products of like quality exposed to ordinary light for the same period, as compared to the tobacco product protected by the chlorophyll green wrapper, had acquired a rank smoking quality and suffered a loss of pleasing aroma. Both lots of tobacco products used in this test were protected from moisture.

The use of chlorophyll green wrapper or screen

in the respect disclosed above is found to be the most helpful of the wave lengths of light above 4900 Angstrom units of the spectrum. Orange yellow wrappers are next in order of beneficial results. The other wave lengths of light above 49 Angstrom units of the spectrum also have a beneficial effect on the products but are not as valuable in this respect as are the chlorophyll green and orange-yellow wrappers.

Such products, if protected, from ultra-violet, 10 violet and blue light rays and exposed to chlorophyll green or orange-yellow wave lengths of light during the curing period, or at any stage thereafter, acquire a noticeably superior smoking quality, flavor and aroma.

Air curing of such products may be done under the influence of the particular protective light screen disclosed by admitting only those helpful rays to the products. Tobacco may be cured in barns which are constructed to admit only chlorophyll green rays of light and thereafter the tobacco products should be enclosed in transparent or translucent chlorophyll green or orange-yellow wrappers or containers which, in addition to their beneficial effectiveness, possess an attractive appearance.

After the tobacco is ready for consumption and has been previously irradiated with rays of light above 4900 Angstrom units of the spectrum, all rays of light, including the harmful ultra-violet, 30 violet and blue rays, may be excluded by enclosing the processed tobacco product in opaque containers with beneficial results, but the packaged product is not as attractive from a sales point of view.

A particularly attractive, protective and efficient cigarette or cigar package may be formed by wrapping or enclosing the cigarettes or cigars in a chlorophyll green or orange-yellow transparent or translucent wrapper or container, the ends of which have an inner layer lining of binder, such as one of the foils. This binder material or foil associated with the ends of the wrapper serves to hold the folded or closing portion or the twisted ends (in the case of a single cigar) of the protecting color screen in a closed position. The binder material or foil may be secured to the ends of the colored wrapper and extend beyond the wrapper. In this form, the binder material must be opaque, and alone serves as a closing medium. The opaque binder material excludes all harmful light from the tobacco at the ends of the package.

If the tobacco be subjected to light rays above 4900 Angstrom units of the spectrum during the curing period, the likelihood of the development of mold or other deteriorating agents is reduced to a minimum or entirely eliminated. If the tobacco product be subjected to such rays during either or both the fermentation and aging periods, the length of time required for those periods will be materially shortened, or the two may be entirely eliminated with certain types of tobacco or kinds of tobacco products if the tobacco has been previously properly treated with such rays.

It is not known what the chemical changes are that take place while tobacco is being irradiated with rays of light having a wave length above 4900 Angstrom units of the spectrum, but it is known that changes do occur. For instance, it has been found by experiment that if cigars be cut in two and one end be subjected to chlorophyll green rays for a period of a few days and the other not, and then each be subjected to the

photographic film test (a test where a sensitized film is exposed in the dark for a length of time to the material under investigation, tobacco in this case), the film exposed to tobacco which had been subjected to such rays will be fogged while the other will not, thus proving that the treated portion has undergone a chemical change. Furthermore, it has been demonstrated that tobacco subjected to the chlorophyll rays appreciably darkens the film more than the tobacco enclosed in foil and which has not been so exposed.

The change in smoking characteristics, flavor and aroma is also noted. Although the changes in flavor and aroma are not chemically determinable according to Johnson—"Studies on the Fermentation of Tobacco"—published in the "Journal of Agricultural Research", vol. 49, No. 2, pages 1 and 150, nevertheless, they are easily detected by organoleptic tests which, according to 20 Johnson, even for fine distinctions, "may be, for all practical purposes, sufficiently reliable", page 150.

Tests also show that the nicotine content or composition of tobacco treated with such rays is different from that contained in tobacco not so treated. What these varied chemical changes are is not known and any theory advanced would be but little better than a guess. It is known that nicotine exists in the tobacco plant in the 30 form of a free base, which is volatile, and in the form of a salt that is not volatile. (Chemical Investigations of the Tobacco Plant by Vickery, Pucher, Wakeman, and Leavenworth, 1933, page 20.) It is also known that there is a material 35 reduction in the volatile alkaloid content of tobacco so treated and this is true whether the tobacco be treated during any of its processing stages or subsequent thereto. Tests have shown that there is a material reduction in the volatile 40 nicotine content of tobacco even when it is treated after it is ready for the market.

Without committing myself to any theory as to the chemical changes effected, it is believed that probably light rays above 4900 Angstrom 45 units when admitted alone to the tobacco during any period of its processing or after it is prepared for the market, may cause, among other things, changes in the state of the nicotine composition by stabilizing combined nicotine molecules or by 50 causing chemical changes where the volatile nicotine constituents are removed or rendered less volatile so that in smoking, for instance, there will be little or no volatile nicotine freed from the tobacco in advance of the actual burning 55 thereof, or at least the amount will be materially reduced. In tobacco processed in the conventional manner in a considerable portion of the nicotine content thereof is volatile and is volatilized in smoking cigars or cigarettes immediately in advance of the burning thereof and it is this volatilized nicotine or like alkaloid substances that are so irritating to the mucus membrane of the mouth and throat of the smoker. This volatile nicotine composition is volatilized 60 by heat in advance of the actual burning, whereas, nicotine in the form of a salt or stable form is actually burned and when burned in smoking, is practically harmless.

In my curing operation and in my operation 70 substitutive of aging, I subject tobacco to light above substantially 4900 Ångström units and exclude from said tobacco all light below substantially 4900 Ångström units of the spectrum at 75 any time between the harvesting of the tobacco

and its actual consumption. Accordingly, my invention is applicable not only before the tobacco is put into packages for sale to the consumer but equally as well while in such package, all for the purpose of eliminating, among other irritating constituents, volatile nicotine.

By chlorophyll green is meant any green pigment having the spectral transmission of the green pigment in plants and having approximately a spectral transmission beginning with 10 5270 to and including 6500 Angstrom units of the visible spectrum.

By orange-yellow is meant that shade of yellow which excludes or absorbs that portion of the spectrum lying below 5,000 Angstrom units 15 of the spectrum.

For the purpose of illustration the accompanying drawing shows two methods by which this invention may be practiced. Figure 1 is a perspective view of cigars 3 enclosed in a transparent container 4. Said container constitutes a light filter which excludes all light below 4900 20 Angstrom units and admits all light above 4900 Angstrom units. This filter may be of other designs. For example, it may be translucent instead of transparent, and it may exclude all light below 4900 Angstrom units and admit light within the range of 4900 to 6500 Angstrom units. The important thing is for the filter to exclude 25 all light below 4900 Angstrom units.

Figure 2 is a cross sectional view of an ordinary 30 tobacco curing barn or any other suitable building. The roof 5 is a light filter of glass, or any other suitable material, designed to create the same effect as the container 4 of Figure 1, hereinabove described. Tobacco bunches 6 are suspended from horizontal rods 7, said rods being supported by stanchions 8.

I claim as my invention:

1. The process of curing tobacco products, 40 which comprises inclosing the tobacco products in containers having a spectral transmission of only above 4900 Angstrom units of the spectrum and exposing the inclosed tobacco products while in the containers to such spectral transmission.

2. The process substitutive of aging while curing tobacco which comprises subjecting the tobacco to the influence of light waves of a selected spectral region above substantially 4900 Angstrom units of the spectrum only.

3. The process of curing tobacco which comprises subjecting the tobacco to the influence of light above substantially 4900 Angstrom units of the spectrum only.

4. An article of commerce comprising a tobacco product which has been cured by the influence of light above substantially 4900 Angstrom units of the spectrum only, and below 6500 Angstrom units.

5. An article of manufacture comprising a tobacco product which has been protected from harmful light during the curing stage with a color screen having a spectral transmission of substantially 5270 to and including 6500 Angstrom units.

6. An article of commerce comprising a tobacco product which has been protected during the curing stage from light substantially below 4900 Angstrom units, and which has been subjected to the influence of light above substantially 4900 Angstrom units.

7. The process of treating harvested tobacco housed in a chamber of substantial size characterized in that it is ordinarily not carried about on the person, wherein the tobacco is subjected 70 to 75

to the influence of light above substantially 4900 Angstrom units of the visible spectrum only.

5. A method substitutive for the aging process of tobacco which method comprises subjecting the tobacco to the influence of light above substantially 4900 Angstrom units of the spectrum only.

9. The method substitutive of aging tobacco products which method comprises subjecting said products to light whose wave lengths are above substantially 4900 Angstrom units and excluding from said products light whose wave lengths are substantially below 4900 Angstrom units. 5
